UNITED STATES PATENT OFFICE

ENOCH A. CARLSON, OF DELVALLE, TEXAS

TWINE HOLDER

Application filed November 15, 1927. Serial No. 233,479.

This invention provides a holder and automatic take-up for twine or cord, such as generally used in stores for tying bundles and packages, and aims to devise an article embodying a few number of parts, simple in construction, durable, efficient and not liable to disarrangement.

The invention contemplates a one piece frame including a bobbin support, and an automatic take up pivoted to the frame, said parts having openings formed therein through which the twine is rove for proper guidance.

The invention consists of the novel features, details of construction and arrangement of parts hereinafter described, particularly claimed and illustrated in the accompanying drawings, in which,

Figure 1 is an elevational view of a twine holder embodying the invention.

Figure 2 is a similar view of a slight modification.

Figure 3 is a fragmentary view in perspective.

Corresponding and like parts are referred to in the following description and designated in the several views of the drawing by like reference characters.

The frame forming the body of the holder comprises an upright 1, an upper member 2 and a lower member 3, the two members 2 and 3 projecting in the same direction from the upright 1 and forming a part thereof. The frame is preferably constructed of a metal strap of a gage to insure stability. A bobbin support 4 projects upwardly from the lower member 3 and consists of a portion bent upwardly into the form of a loop. A metal strap 5 is riveted or otherwise secured to the upper portion of the upright 1 and extends some distance above the member 2. A pivot 6 is retained in place by means of the strap 5 which is crimped to extend about the pivot and confine it to the upright 1. A take-up lever 7 is mount-

ed upon the pivot 6 and is weighted at its rear end to normally hold its forward end elevated, whereby to lift the loose end of the twine or cord and hold it out of the way and in determinate position to be conveniently grasped. In the form shown in Figure 3 suspending means 8 may be attached to the upper end of the strap 5. In the form shown in Figure 2 a stout wire 9 is engaged at one end with the strap 5 and at its opposite end with the member 2 and this wire is curved upwardly intermediate its ends to receive a suspending device 10.

The numeral 11 designates a bobbin of twine or cord which is slipped upon the support 4 and which when pressed downwardly upon the support engages the lower member 3 at opposite sides of the support. The cord or twine is passed upwardly through an opening 2^a formed in the member 2, thence through openings 5^a formed in the upper portion of the strap 5, thence through openings 2^b formed in the member 2 and upwardly through an opening 7^a formed in the outer end of the take-up lever 7, after which it is passed through openings 2^a and 3^a in the forward ends of the members 2 and 3. In this manner the cord is prevented from running off too freely from the bobbin, and by passing downwardly through openings in the outer or forward ends of the members 2 and 3 is prevented from interfering with the bobbin or parts of the holder. Should it be elected to mount the holder upon a supporting member as 11^a, as indicated by the dotted lines in Figure 1 the forward end of the lower member 3 projects sufficiently beyond said member to prevent interference thereof with the downwardly extending portion of the cord or twine, as will be readily understood.

Having thus described the invention, I claim:

A twine holder comprising a frame

formed of a metal strap including an upright, upper and lower members projecting laterally in the same direction from the ends of the upright to a like extent, the lower member having an intermediate portion bent upwardly to provide a loop shaped bobbin support, and a take-up lever mounted upon the upper portion of the said upright, the said take-up lever and the outer ends of the upper and lower members of the frame having openings formed therein through which the twine or cord is passed for proper direction.

In testimony whereof I affix my signature.

ENOCH A. CARLSON. [L. S.]
